(57) **CLAIM**

The ornamental design for a taxi-top advertising unit, as shown and described.

DESCRIPTION

FIG. 1 is a side perspective of our new design for a taxi-top advertising unit according to the present design, the opposite of which is symmetrical;

FIG. 2 is an enlarged elevational view of one end of the taxi-top advertising unit of FIG. 1, the opposite end of which is identical; and,

FIG. 3 is a reduced scale perspective view of the taxi-top advertising unit of FIG. 1.

A view of the bottom of the taxi-top advertising unit has been omitted since it is flat and unornamented. The broken lines are for illustrative purposes only and form no part of the claimed design.
